(57) CLAIM

The ornamental design for a garment as shown and described.

DESCRIPTION

Fig. 1.1 is a front perspective view of a garment, showing a first embodiment;

Fig. 1.2 is a rear perspective view thereof;

Fig. 1.3 is a side view thereof;

Fig. 2.1 is a front perspective view of a garment, showing a second embodiment; and

Fig. 2.2 is a rear perspective thereof.

The portion of the design shown in the color purple is for the purpose of illustrating a seam in the garment and forms part of the claimed design.
